[57] **CLAIM**

The ornamental design for a portable two-way radio communications device, as shown and described.

DESCRIPTION

FIG. 1 is a front, top and right side perspective view of a portable two-way radio showing our new design; FIG. 2 is a rear elevational view thereof; FIG. 3 is a left side elevational view thereof; and, FIG. 4 is a bottom plan view thereof. The broken line showing of an Antenna in FIGS. 1, 2 and 3 is for illustrative purposes only and forms no part of the claimed design.

*FIG. 1**FIG. 2*

FIG. 3

FIG. 4
